Primary Examiner — Amy C Wierenga(57) **CLAIM**

The ornamental design for a cuisine plate as shown and described.

DESCRIPTION

FIG. 1 is a top perspective view of a cuisine plate showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 7;

FIG. 10 is a cross-sectional view taken along line 10-10 of FIG. 7; and,

FIG. 11 is an enlarged view of portion 11 in FIG. 1. The dot-dashed lines illustrate the boundary of the enlarged view and form no part of the claimed design.

1 Claim, 11 Drawing Sheets(56)
